US00D482413S

(12) **United States Design Patent** (10) Patent No.: **US D482,413 S**
Manville (45) Date of Patent: **** Nov. 18, 2003**

(54) **DESIGN CRAFT KIT CONSTRUCTION
COMPONENT—TRANSPARENT/
TRANSLUCENT, STYLIZED SPOOL FORM**

(75) Inventor: **Richard B. Manville**, Los Angeles, CA
(US)

(73) Assignee: **Mattel, Inc.**, El Segundo, CA (US)

(**) Term: **14 Years**

(21) Appl. No.: **29/158,010**

(22) Filed: **Mar. 26, 2002**

(51) LOC (7) Cl. **21-01**

(52) U.S. Cl. **D21/484**

(58) Field of Search D6/511; D20/22-28;
D21/386, 390, 437, 478-480, 484, 489-492,

Primary Examiner—Sandra L. Morris

(74) Attorney, Agent, or Firm—Kolisch Hartwell, P.C.

(57) **CLAIM**

The ornamental design for a design craft kit construction component—transparent/translucent, stylized spool form, as shown and described.

DESCRIPTION

FIG. 1 is a perspective view of the invention; and,
FIG. 2 is a plan view of the invention.

1 Claim, 1 Drawing Sheet
